UNITED STATES PATENT OFFICE.

GEORGE W. MEYER AND CHARLES A. ROOS, OF CINCINNATI, OHIO.

LIFTING-JACK.

1,395,650.

Specification of Letters Patent.

Patented Nov. 1, 1921.

Application filed September 27, 1920. Serial No. 413,238.

To all whom it may concern:

Be it known that GEORGE W. MEYER and CHARLES A. Roos, citizens of the United States, residing at Cincinnati, in the county 5 of Hamilton and State of Ohio, have invented new and useful Improvements in Lifting-Jacks, of which the following is a specification.

Our invention relates to the class of implements commonly known as lifting "jacks"; its object being to provide a jack adapted to operate not only upon the ground or similar support, but upon a post or equivalent element such as the relatively fixed or basic 15 member of an extensible shore, to elevate the adjustable member upon and in relation to said post.

To this end our invention consists in a jack provided with means for adjustable 20 self-support upon a relatively fixed post and thereby to act upon an extensible element employed in connection therewith. While especially useful in extensible shores, other uses will readily suggest themselves.

25 In the drawings herewith submitted illustrative of the specification:

Figures 1 and 2 are vertical elevations in cross planes of a lifting jack of common type embodying our invention; and

30 Fig. 3 is a plan view of the structure as seen from above.

Referring now to the drawings, A designates the supporting body or frame of a lifting jack of the central screw type, provided 35 with the combined ratchet wheel and bevel gear B, the bevel pinion b operating screw C, and minor adjuncts such as handle b¹, ratchet pawl b², etc., all as found in lifting jacks in common use in automobile service, etc., and 40 require no further description.

In carrying out our invention, we provide the containing frame A with a side lug D perforated horizontally from side to side to admit a pivot stud or bolt f on which is carried a holding plate E¹ formed or provided 45 with side ears e extending downwardly at opposite sides of the lug D and having perforations registering with that of the lug D to admit and seat the stud or bolt f, in such 50 wise as to permit a slight pivotal action by the plate E¹.

The plate E¹ as shown in the illustration, extends outwardly and is formed with a U-shaped side opening to admit and seat the 55 plate horizontally on a post or tubular ele-

ment P upon which it is adjustable by manipulation of the plate as "canting" lock by a slight pivotal movement out of the horizontal as indicated in Fig. 1 of the drawing, and is thus susceptible of a "following up" 60 adjustment to engage at any elevation on the post P limited only by the general conditions of adjustability of the parts concerned.

In order to keep the implement in proper longitudinal relations with the post P, we 65 provide, in addition to the plate E¹ which prevents displacement only at the open side, a similar plate E² fixedly secured at the bottom of the jack frame A, having an opening registering with but opening outwardly at 70 a right angle with that of plate E¹.

Plates with larger or smaller openings and conformably shaped, may be substituted according to requirements of use.

The jack by its weight, especially when 75 increased by the load carried thereby, causes the plate E¹, by its pivotal action to assume a canting relation to the post P, thereby causing the upper and lower edges or curbs of the perforation in plate E¹ to seat firmly 80 against the post at opposite sides as clamping elements moving toward each other; producing a holding force increased by relatively downward pressure on the jack.

By lifting the jack or slightly depressing 85 the outer side of the plate E¹ into a horizontal position in relation to the post, the position of the jack may be re-adjusted to a higher or lower point as desired.

We claim as our invention and desire to 90 secure by Letters Patent of the United States:—

1. In combination with a telescopic lifting jack, a perforated canting plate pivotally secured at one side to the frame of the jack 95 and adapted to embrace and engage a supporting post at opposite sides at right angles with the line of its pivot in a canting relation of contact with the opposite edges or curbs of the plate perforation.

2. A telescopic lifting jack provided with a side lug and a plate pivotally secured thereto, having a side recess adapting it to engage the jack removably upon a post or upright and assume a canting or clamping relation of engagement therewith, at opposite sides of the post, thereby supporting the jack as a basis for its own lifting action.

3. In a telescopic lifting jack of the character indicated, a laterally extended plate 110

having a U-shaped opening outwardly at a right angle with the general line of extension, and a second plate spaced apart from the first, with a similar opening extended outwardly at a right angle with that of the first plate whereby the jack may be manually placed upon or removed from a basic support and held in parallel relations of engagement therewith while being operated.

In testimony whereof we have hereunto set our hands in presence of two subscribing witnesses.

GEORGE W. MEYER.
CHARLES A. ROOS.
